(57) **CLAIM**

The ornamental design for a sensor system for a fitness machine, substantially as shown and described.

DESCRIPTION

FIG. 1 is a depiction of a perspective view of the sensor system for a fitness machine.

FIG. 2 is a depiction of a perspective view of a first sensor of the sensor system isolated from the fitness machine.

FIG. 3 is a depiction of a front view of the isolated first sensor.

FIG. 4 is a depiction of a side view of the isolated first sensor.

FIG. 5 is a depiction of a top view of the isolated first sensor.

FIG. 6 is a depiction of a back view of the isolated first sensor.

FIG. 7 is a depiction of a side view of the isolated first sensor.

FIG. 8 is a depiction of a bottom view of the isolated first sensor.

FIG. 9 is a depiction of a perspective view of a second or third sensor of the sensor system isolated from the fitness machine.

FIG. 10 is a depiction of a side view of the isolated second or third sensor.

FIG. 11 is a depiction of a front view of the isolated second or third sensor.

FIG. 12 is a depiction of a top view of the isolated second or third sensor.

FIG. 13 is a depiction of a back view of the isolated second or third sensor; and,

FIG. 14 is a depiction of a bottom view of the isolated second or third sensor.

The broken line showing of a sensor system for a fitness machine is included for the purpose of illustrating environment in which the claimed design is embodied and forms no part of the claimed design.
